STACKED ARTICLE DISPENSER

Harold L. Hilton, Terrace Park, Henry C. Hilton, Cincinnati, and Huston L. Hargett, Madeira, Ohio; said Hargett assignor to said Harold L. Hilton and said Henry C. Hilton

Application November 22, 1946, Serial No. 711,698

2 Claims. (Cl. 312—67)

1

Our present invention relates to an improved stacked article dispenser and more particularly to the type of dispenser which may be well applied in both restaurant and domestic use for storing and dispensing slices of bread or similar articles so that the bread slices stacked in the dispenser will not be touched after stocking the device except by the person proposing to consume the same.

The stocking of such a device will effect a saving in bread and will permit the ready withdrawal of the desired slice or slices as the consumer wishes.

In the accompanying drawings we have illustrated one complete example of the physical embodiment of our invention according to the best mode we have thus far devised but it will be understood that various changes and alterations may be made in the exemplified structure within the scope of the appended claims.

In the drawings:

Figure 1 is a side elevational view of the dispenser of our invention.

Figure 2 is an end elevational view thereof.

Figure 3 is a vertical sectional view taken at line 3—3 of Figure 4.

Figure 4 is a vertical sectional view taken at line 4—4 of Figure 3.

Figure 5 is a horizontal sectional view taken at line 5—5 of Figure 1.

Figure 6 is a horizontal sectional view taken at line 6—6 of Figure 3.

Figure 7 is a detail view of the drawer construction with one drawer open.

Figure 8 is a similar view with the opposite drawer open.

Figure 9 is a detail view of the base of the dispenser.

Figure 10 is a vertical sectional view through the base showing one end wall of the base and its support for the case.

Figure 11 is a plan view of the drawer.

Referring now to the drawings wherein like characters indicate like parts we have illustrated the present embodiment of our invention as comprising a pedestal 2, as shown in Figures 1 and 2, or feet 2^a as shown in Figures 3, 4, 7, 8, 9 and 10, as a support for the box-like base 4 of the dispenser, the base having end walls 6 extending upwardly from the base, and formed with interior shoulders 8 to securely receive and retain the cover or case 10. Handles 12 are provided on the case to facilitate removal thereof. The case is also provided with a removable partition 14 which is mounted in grooves 12^a in the lateral sides of the casing and in recesses 8^a in the shoul-

2

ders 8. The lower corners of the partition are notched to accommodate the shoulders 8.

The base is also fashioned with a lower shoulder 16, and the bread slices 18 rest in one stack upon the support or slider 20 which is slidable on the lower edges of the flanges 22 on the base.

Within the base we employ a lower open frame formed with a pair of side bars 24 the lower edges of which are curved at 26 to conform to the base and a rod or wire connector between the frame elements indicated at 28 is positioned under the support 20 between the flanges 22. A second upper open drawer frame having spaced side bars 30 is slidably supported upon the lower frame and a rod or wire connector 32 is also positioned under the support 20 between the flanges 22 and above the wire 28. Outer flanges or heads 34 on the drawer frames limit the inward movement thereof while the handles 36 provide a ready means for withdrawing a drawer frame.

With the case stocked with two stacks of bread slices on opposite sides of the central partition, one stack will rest on the support while the other stack rests upon the base, the lowermost slices being confined within the open frame of the drawer 24 as seen in Figure 3. With both drawers closed the wires 28 and 32 are substantially central of the device, and when the lower drawer 24 is withdrawn as seen in Figure 7, the bread slice confined therein will be withdrawn and will drop as shown through the withdrawn open frame. Successively following the withdrawal of the said frame, the support will be pulled by the wire 28 to the position of Figure 5 preventing the lowering of that stack of slices, and permitting the lowering of the left hand stack of slices. The lower drawer 24 may now be returned and the wire 28 will slide along under the support without moving the said support and both drawers will be centered.

The upper drawer frame 30 may be opened now dispensing the lowermost slice of the left hand stack, the wire 32 thereby pulling the support following the bread slice into position under the left hand stack, and the steps will be repeated so long as the drawers are alternately opened and closed.

From the above description of the construction and operation of the device of our invention it will be apparent that the device will dispense fresh bread slices alternately from each side through the drawer frames therein until the stacks are exhausted. It will then be necessary to remove the case placing two stacks of bread slices therein, and immediately without further

attention, the device is ready for operation as the lowermost slice of one stack will fall into the frame not covered by the support.

The case, and in fact the entire structure may be made of suitable material such as plastic, transparent or opaque and the dispenser will provide an attractive and efficient addition to the dining table whether in the restaurant or in the home.

Having thus fully described our invention what we claim as new and desire to secure by Letters Patent is:

1. A dispenser for stacked articles comprising a box-like base with the upper end open and having openings extending across two opposite sides, a box-like cover positioned on the base and extending upward therefrom, a hollow slider having an upper horizontally disposed panel with downwardly positioned flanges at the ends, the length of the said slider being greater than one-half of the width of the base, a pair of spaced lower side bars positioned on the base and at opposite sides of the slider, a head connecting the outer ends of the side bars having a handle on the outer surface and closing the opening at one side of the base in the closed position, a transverse rod intermediate of the length of the side bars extending through the slider and with the ends thereof carried in the side bars, a pair of spaced upper side bars positioned on the lower side bars and on opposite sides of the slider, a head connecting the outer ends of the upper side bars having a handle on the outer surface closing the opening in the base opposite to that closed by the head of the lower side bars, in the closed position, and a transverse rod intermediate of the length of the upper side bars extending through the slider and with the ends thereof carried in the upper side bars.

2. In a dispenser for dispensing slices of bread from stacks thereof, the combination, which comprises, a box-like base supported on a pedestal

with the upper end of the base open and with openings extending across two opposite sides, a box-like cover having a dividing vertically disposed partition intermediate of the width thereof removably mounted on the base and extending upward therefrom, a hollow slider having an upper horizontally disposed bread holding panel with downwardly extending flanges at the ends, the length of said slider being greater than one-half of the width of said base, a pair of spaced lower side bars positioned on the base and at opposite sides of the slider, a head connecting the outer ends of the side bars having a handle on the outer surface and closing the opening at one side of the base in the closed position, a transverse rod intermediate of the length of the side bars extending through the slider and with the ends thereof carried in the side bars, a pair of spaced upper side bars positioned on the lower side bars and on opposite sides of the slider, a head connecting the outer ends of the upper side bars having a handle on the outer surface closing the opening in the base opposite to that closed by the head of the lower side bars, in the closed position, and a transverse rod intermediate of the length of the upper side bars extending through the slider and with the ends thereof carried in the upper side bars.
